Filed Feb. 11, 1959, Ser. No. 54,554

(Cl. D15—1)

The side of the chair not shown is the same in appearance as side shown while the back of the chair is conventional in that it terminates adjacent the top of the seat and its rear face has an appearance similar to its front face.

The dominant features of my design constitute a substantially squirrel shaped representation including block-like supporting feet and a rounded tail portion having an opening therein, in combination with the remaining features of the design.

I claim:
